CAR SEAL

Douglas Willard Ashton, Ottawa, Ontario, Canada,
assignor to J. O. Ker, Ottawa, Ontario,
Canada

Application July 20, 1939, Serial No. 285,605

3 Claims. (Cl. 292—322)

This invention relates to car seals. Many different types and structures of car seals have been previously proposed. In a great many of these proposals the main object has been to produce

- 5 a one piece seal with the casing blanked out together with the locking strip. Such proposals, however, are disadvantageous, particularly from the point of view of the amount of material necessary and the waste of material apart from complication of manufacture. Other proposals have involved the use of separate housings and locking strips subsequently connected together, with a view to avoiding the difficulties of the amount of material used and loss of material through waste.
- 10 15 Such latter proposals, while in many cases avoiding the difficulties stated, are objectionable from the point of view that they still retain the difficulty of complication in manufacture and assembly, while in many cases they do not provide for a strong non-tamper proof seal.

The present invention relates to a seal of the second mentioned class wherein the housing and locking strips are formed separately from one another and a main object of the invention is to provide a seal wherein the parts may be formed separately by simple operations and may be united in a particularly simple manner to provide in effect a one piece seal.

A further object of the invention is to provide 30 a device of this character which may be so constructed as to provide a particularly strong seal which cannot be tampered with successfully without destroying the seal.

A still further object of the invention is to provide 35 a device of this character which may be quickly manufactured in quantity and which may be produced at low cost.

With these and other objects in view the invention resides generally in a car seal embodying a strip of material formed with a hook-shaped locking tongue at one end and a walled receiving chamber adjacent the other end pressed from the plane of the strip, the chamber having an accessible opening facing the end of the strip to 40 which it is adjacent to permit entry of the locking tongue to the chamber, the end of the strip carrying the chamber being enclosed by a housing walled on all sides and open at one end so as to encase the chamber but permitting entry of the locking tongue thereto, the housing being integrally connected with the strip, and the chamber and locking tongue having co-operating means to retain the tongue when inserted in the chamber and thus hold the tongue within the housing.

55 The invention will be fully appreciated from

a consideration of the following detailed specification taken in conjunction with the accompanying drawing.

In the drawing,

Figure 1 is a perspective view of the seal according to the present invention with the locking tongue secured within the housing.

Figure 2 is a perspective view of the locking strip reversed and showing the housing in dotted lines.

Figure 3 is a plan view of one side of the locking strip.

Figure 4 is a side elevation of the locking strip with parts of it shown in section, and

Figure 5 is an enlarged fragmentary section of the seal with the locking strip engaged within the housing.

Referring to the drawing, A indicates the car seal as a whole which includes a locking strip B and a housing C. The locking strip B is formed at one end with a hook-shaped locking tongue 10 which is orificed as at 11 to co-operate in the locking of the tongue within the housing C. The opposite end of the locking strip is provided with complementary means to receive the hook-shaped tongue, in the form of a walled receiving chamber 12 which is formed by pressing a portion of the material from the locking strip, as indicated at 13, in such a manner as to provide a sloped guide-way 14 and an opening 15 facing towards the end 30 of the strip adjacent to which the receiving chamber is formed. As noted in Figure 3, the receiving chamber, or in other words the pressed portion of the locking strip, is of substantial width, leaving comparatively fine margins 16 of the strip of 35 material in the plane of the strip and the opening 15 is of a width to accommodate the width of the locking tongue 10. The main defining wall of the receiving chamber 12 has a lug 17 struck from it so as to project within the chamber, this lug being preferably pointed, as indicated at 18 (Figs. 2 and 3).

The housing C is designed to be fitted over that end of the locking strip carrying receiving chamber 12 and upon reference to Figure 5 it will be seen that the bottom wall 19 of the housing C forms the bottom wall of the receiving chamber 12 so that this receiving chamber is closed completely on all sides and the only access thereto is by way of the opening 15. The housing C is formed of such a depth as to accommodate the receiving chamber and permit a space 20 between the top of the receiving chamber and the top wall of the housing which forms a passageway for the insertion of the locking tongue and of the strip.

The housing C is designed to be connected with the locking strip by way of spot welding, as indicated at 21 and the bottom wall of the housing is preferably extended in the form of an apron 22 which facilitates the welding operation as it permits the welding point to be positioned outside the housing, while on the other hand the apron 22 forms a reinforcement for the locking strip at a point where strain may 10 ordinarily occur.

It will be appreciated that the locking strip may be assembled and united to the housing C in a very simple operation by reason of the fact that the locking strip is provided with a spacer 15 23 which constitutes that part of the material of the strip in advance of the receiving chamber 12 and terminating in that end of the strip adjacent to which the receiving chamber is formed. Thus by employing a spacer of this character 20 positioned in the plane of the strip and in advance of the receiving chamber, it is obvious that the operation of assembly merely requires the insertion of that end of the locking strip in the housing, whereupon all parts are immediately 25 positioned in their proper relation with one another so that the assembly of the housing and locking strip merely constitutes a routine operation which can be effected substantially simultaneously with the welding operation and all 30 seals so manufactured must necessarily be identical.

In locking the seal it will be appreciated that it is only necessary to bend the locking strip and insert the hooked locking tongue in the housing. 35 In this instance, the inclined guideway 14 formed on the wall of the receiving chamber 19 guides the locking tongue to the passageway 20 and the locking tongue may be moved to the inner end of the housing, at which point the extreme 40 end 24 of the locking tongue will pass the inner end 25 of the top wall of the receiving chamber so that the end 24 of the tongue may then be positioned in line with the opening 15 of the receiving chamber. Upon pulling that part of 45 the strip carrying the locking tongue, the locking tongue will enter the receiving chamber and will tend to deflect the lug 17 such that it will finally lodge in the orifice 11 in the locking tongue, as shown in Figure 5. Thus, the locking tongue 50 cannot be disengaged from the lug or removed from the receiving chamber without breaking the seal.

Attention is directed to the fact that in attempting to pull upon that portion of the locking 55 strip carrying the locking tongue, the bent or hooked portion of that end of the strip will bear against the inner end 25 of the top wall of the receiving housing and this will relieve strain on the lug 17 under such conditions. However, a 60 continued pull on this part of the strip would still be firmly resisted by the locking means by reason of the fact that the lug 17 would bear against the bottom wall 19 of the housing C and

strongly resist any attempt to pull the locking tongue from the housing. Thus a very sturdy structure is produced which is enhanced by the fact that the top wall 13 of the receiving chamber, which acts as a resisting agent in the case 5 of the strip being pulled in this manner, is an integral part of the strip by reason of the fact that it is part of that portion pressed from the strip. Therefore it will not have any tendency to bend and double under any strain imposed 10 upon it as such tendency is immediately offset by the side walls which join the top wall 13 with the strip.

It will further be appreciated that since the sides of the receiving chamber 12 are substantially close to the marginal edges of the strip, there is very little space left between the sides of the receiving chamber and the side walls of the housing C. Thus it is not possible for one 15 to insert an instrument into the housing which 20 will have any effect in an attempt to disengage the locked parts.

From the foregoing it will be appreciated that the seal of the present invention is one which is sturdy of construction, is tamper-proof and 25 may be manufactured and assembled in simple operations at low cost and without waste of material in its manufacture.

What I claim is:

1. A seal comprising a strip of material formed 30 with a hook-shaped locking tongue at one end and a rigid walled receiving chamber located substantially at the other end pressed from the plane of the strip, said chamber having an accessible opening facing the end of the strip to which it 35 is adjacent and designed to permit entry of the locking tongue to the chamber, a housing walled on all sides and open at one end designed to fit over one end of the strip and encase the receiving chamber, the housing being integrally connected with said strip, said open end forming an entrance to the housing whereby the locking tongue may be inserted in said housing, retaining means within the receiving chamber and co-operating means carried by the locking tongue 40 whereby said tongue is retained when inserted in said chamber and held within the housing.

2. The device as claimed in claim 1, in which the retaining means for the chamber is in the form of an inclined lug struck from a wall of 50 the chamber and projecting therewithin, in a direction opposed to the opening to the chamber, the locking tongue being formed with an orifice designed to be traversed by the lug when the tongue enters the chamber.

3. The device as claimed in claim 1, in which the bottom wall of the housing is extended beyond the other walls forming an apron contiguous with a portion of the strip outside the housing and providing a means for connecting the 60 strip to the housing.

DOUGLAS WILLARD ASHTON.
